UNITED STATES PATENT OFFICE.

PHILO S. WHITE, OF PROVIDENCE, RHODE ISLAND.

IMPROVEMENT IN FASTENINGS FOR NECKTIES.

Specification forming part of Letters Patent No. 97,331, dated November 30, 1869; antedated November 24, 1869.

To all whom it may concern:

Be it known that I, PHILO S. WHITE, of Providence, in the county of Providence and State of Rhode Island, have invented a new and useful Improvement on Neckties; and I do hereby declare that the following is a full and exact description thereof, reference being had to the accompanying drawings, and to the letters of reference marked thereon, in which—

Figure 1 is a perspective view of my invention. Fig. 2 represents my improvement as attached to a necktie. Figs. 3 and 4 are detailed parts.

In the accompanying drawings, A and B, Fig. 3, are two thin plates of metal, having two holes in each.

C, Fig. 1, is a wire, bent oblong from its center, to form a spring-loop, and brought nearly together at the points at *d* and *e*. This wire is then curved or bent from *d* and *e*, and the ends are fastened through the holes in the plates A and B, as shown in Fig. 4, the dotted lines in same figure representing the thickness of a necktie, to which it is fastened. The two plates A and B serve to hold the spring-loop C firm when attached to a necktie, as shown in Fig. 2.

To use my invention, the curve on C at *d* and *e* is pressed back of the button on a shirt that fastens the neckband together. The loop springing open, the button passes between the necktie and wire C, bringing the spring-loop back of the button and spanning the button fastening or thread. The points at *d* and *e* springing together prevent the necktie from dropping off when worn on the neck. It can be easily put on and taken off, which is an advantage.

I do not claim a necktie as my invention; but

What I do claim, and desire to secure by Letters Patent of the United States, is—

The improved necktie-fastening herein described, consisting of the wire yoke C, in combination with the perforated plates A and B, all constructed and arranged substantially as shown, for the purpose specified.

PHILO S. WHITE.
